UNITED STATES PATENT OFFICE.

FRANK O. SHERIDAN, OF COVINGTON, KENTUCKY, ASSIGNOR OF ONE-FOURTH TO RICHARD J. DIBOWSKI AND ONE-FOURTH TO PHILLIP METZ, BOTH OF COVINGTON, KENTUCKY; MARY SHERIDAN EXECUTRIX OF SAID FRANK O. SHERIDAN, DECEASED.

VALVE.

1,197,583.

Specification of Letters Patent.

Patented Sept. 5, 1916.

Application filed April 10, 1915. Serial No. 20,549.

To all whom it may concern:

Be it known that I, FRANK O. SHERIDAN, residing at Covington, Kenton county, State of Kentucky, have invented certain new and useful Improvements in Valves, of which the following is a clear, full, and exact description, attention being called to the drawing which accompanies this application and forms a part thereof.

10 This invention concerns valves used for the purpose of controlling passage of liquid matter through conduit pipes. It relates more particularly to such valves which are used in connection with the service-pipes, 15 mains and branches thereof, of water-supply systems.

The object of the invention is to construct such valves in a manner that they may be readily operated and maintained in operative condition, that they move freely and that they are not subject to the effects of obstructions.

The invention consists of the particular construction whereby this object is obtained 25 and as the same is described hereinafter and pointed out in the claim.

In the drawing referred to in said description, Figure 1. is a vertical cross-section of such a valve and shown in connection with a 30 hydrant or fire-plug. Fig. 2. in a similar view shows the valve as used in connection with a main or line-pipe. Fig. 3. is a horizontal section of a certain part shown in Fig. 2 and on a line indicated at 3—3 in 35 said figure.

The valve indicated at A, occupies a position above a horizontal partition 6 which separates two chambers 7 and 8 from each other. These chambers of which the first 40 constitutes the intake chamber, are contained within a housing B and are outwardly open and the housing at its open ends is arranged to permit its interposition and connection to the parts of the water conduit where the 45 valve is to be used.

Valve A is substantially like an inverted cup and telescopes a tubular neck 9 on which it is mounted to move with a sliding fit. Neck 9 projects upwardly from an opening 50 in partition 6, which opening forms an outlet from intake chamber 7. This opening is screw-threaded and neck 9 is removably seated therein. When valve A is in a position as shown in Fig. 1, no water can pass.

When raised to a position as shown in Fig. 55 2, water passes from chamber 7 into chamber 8 through ports 11 which are provided in sufficient number and size in the side of neck 9. The seat of the valve is on the outside 60 of neck 9 and a close fit is obtained by means of packing 12 occupying an annular recess in the edge of the valve and held therein by a ring 13.

In the device shown in Fig. 1, the valve is used for the purpose of controlling water 65 supplied from a branch pipe to a fire-plug 14. The valve housing at one of its open-ends is therefore provided with a socket 15 to permit connection to said branch pipe and formation of a calking joint thereat. 70 At the other open end of the housing a flange 16 is provided to permit connection to the hollow column which forms the fire-plug. Nipples 17 are provided on said plug where hose connection may be made in the 75 usual way after caps 18 have been removed.

In the device shown in Fig. 2, the valve is used to control passage through a pipe line and accordingly the valve housing at both ends is arranged to permit insertion into 80 such a line. A socket 19 to permit connection and formation of a calking joint is provided for the purpose at each end of the housing. In this case the latter is further subdivided by a vertical partition 21, so that 85 direct passage of water through the housing is prevented and limited to ported neck 9, where it is subject to control by valve A. When this latter is open, water from intake chamber 7 passes into chamber 8 and from 90 there by means of a bypass 22 it is deflected within the housing and turned back into the pipe line, in which it passes on.

The valve may be manipulated by any 95 suitable means. In each case it is connected to a valve stem 23. In the case of the fire-plug, the upper end of this stem carries a screw thread which is fitted into an operating nut 24, held against movement in axial direction in the manner shown. The upper 100 end of the nut is square to permit engagement by a key or wrench. Below its screw-threaded portion, the stem has a square portion 25 fitted to a guide plate 26. When nut 24 is turned, stem 23 will move axially, 105 opening or closing the valve according to direction of rotation. No novelty is claimed for the construction of this movement.

In the form shown in Fig. 2, the valve stem is threaded and seated in a bonnet 27 connected to housing B so as to close the open end of chamber 8. The lower end of 5 the stem has a shoulder which is engaged by a cap 28 secured to valve A and whereby this latter is connected to the stem. The upper end of the stem is square to permit engagement by a key for manipulation.

10 When the stem is rotated it moves up or down in the bonnet, according to direction of rotation and moves the valve accordingly.

29 is a stuffing box and 31 is a casing which extends to the surface to permit access to the valve stem from above.

Considering the particular purpose of these valves and their position in the ground below the surface, it is essential that access to the vital parts for their repair or renewal 20 may be had in the most ready manner without taking up the housings and disturbing the pipe lines. As will be seen the construction is such that this is not required and access from above is rendered possible for 25 the purpose of re-packing the valve or renewing the neck upon which it is seated.

Having described my invention, I claim as new:

30 In valve-construction designed for use under ground, the combination of a housing which is open at one end to form an inlet

and is subdivided by an integral horizontal partition to form an inlet chamber between said partition and the inlet and a discharge chamber above said partition, a detachably 35 connected bonnet to close said discharge chamber, an opening in the partition mentioned, a neck seated in this opening with a screw-connection and projecting upwardly from the partition, port-openings provided 40 in this neck which extend from its upper edge downwardly and terminate some distance above the partition, a cup-shaped valve fitted around the outside of said neck and provided with an inturned recess around its 45 lower edge, packing in this recess, a ring to hold this packing in place and to maintain it in fitting contact with the outside of the neck against which the valve is seated and a stem projecting upwardly from said valve 50 and extending through the bonnet mentioned for manipulation from above to adjust this valve with a sliding movement to and from the partition mentioned and between said partition and the upper edge of 55 the neck.

In testimony whereof, I hereunto affix my signature in the presence of two witnesses.

FRANK O. SHERIDAN.
